12 Claims. (Cl. 137—684)

1

This invention relates, in general, to thermoelectrically actuated devices, and has particular relation to thermoelectrically actuated valves, relays, and the like.

Thermoelectric control devices having a thermoelectric generator, the "hot" junction or junctions of which are heated by a pilot burner or other flame whereby to energize an electromagnet having a coil connected in circuit with the thermoelectric generator, to hold an armature in attracted position, and a valve or other controlling member in open or operating position, have been previously provided. The thermoelectric power generated by the heating of the "hot" junction or junctions of such devices has not, however, been sufficient for actuation of the controlling means from one position to another position, particularly a fluid control valve, an amount to provide for opening and closing the same sufficiently for its intended purpose.

One of the main objects of the present invention is to provide an improved form of thermoelectrically actuated device in which the armature moves only a very minute amount (i. e., an amount that can be accomplished by heating the "hot" junction or junctions of the thermoelectric generator), and in which the minute movement of the armature provides for increased movement of the valve, relay member, or other controlling means in amount, for example, for opening and closing of the valve sufficiently for its intended purpose, or for movement of other controlling means a useful amount.

Another object of the invention is to provide a device having a body of liquid or other suitable fluid for providing, by minute movement of the armature, an increased amount of movement of the valve, relay member, or other controlling means, and more particularly, in which different cross-sectional areas of the liquid or other fluid containing chamber at the armature and at the controlling position provide for the increased movement of the valve, relay member, or other controlling means.

Another object of the invention is to provide in a device of the class described means for filling a large portion of the chamber of large cross-sectional area adjacent to the armature and for reducing any volumetric variations in the liquid or fluid body due to changes in ambient temperature.

Another object of the invention is to provide a device of the class described in which there is a diaphragm closing the large cross-sectional area of the liquid or other fluid containing cham-

2

ber adjacent to the armature, and more particularly a device in which there is a second diaphragm which cooperates in the tubular system and in such manner that changes in atmospheric pressure affecting the first-mentioned diaphragm are opposed by pressures acting on the second diaphragm.

Another object of the invention is to provide embodiments of the invention in which, for example, water, or water and alcohol, or other liquids or fluids, or mercury, may be employed for the purposes set forth, and embodiments of the invention for use with fluid control valves, or with control switches, relays, or other control devices.

Another object of the invention is to provide improved forms of devices having various features of novelty and advantages, and which are particularly characterized by their simplicity in construction, their economy in manufacture, and their effectiveness in use.

Further objects and advantages of the invention will appear from the following detailed description, taken in connection with the accompanying drawings which illustrate the manner of constructing and using certain illustrative embodiments of the invention.

In the drawings:

Figure 1 shows more or less diagrammatically thermoelectric control apparatus embodying the present invention as applied for controlling the supply of fuel to a main burner having a pilot burner in juxtaposition thereto;

Figure 2 is a diagrammatic view showing an actuating structure using mercury and applied to control a switch or relay; and

Figure 3 is a diagrammatic view similar to Figure 2 but showing an actuating structure according to Figure 1, and a second diaphragm which cooperates in the tubular system in such manner that changes in atmospheric pressure affecting the first diaphragm are opposed by pressure acting on the second diaphragm.

Referring first to Figure 1 of the drawings, the burner shown at 1 is a main burner. It may be the main burner for a room or space heater, or it may be the burner for a water heater, or for a floor furnace, an oven burner, one or more top burners for a gas range, or any other burner, and of any suitable construction.

A fuel supply pipe or conduit 2 leads to the burner 1 for the delivery of gaseous or other fuel thereto, for example, through a mixing chamber 3 to which air is admitted through adjustable air inlets (not shown), as well understood in the art.

The flow of gas through the conduit 2 is controlled by a valve member 4 which is shown in closed position seated upon an annular valve seat 5 at one end of a valve opening 6 within the valve body shown diagrammatically at 7 on enlarged scale relative to the burner 1. Contiguous sections of the fuel supply pipe 2 are connected to the inlet 8 and outlet 9 of the valve body.

The electromagnet of the thermoelectric control structure shown in Figure 1 comprises a generally U-shaped magnet frame 10 having coils 11 wound about the legs thereof and connected in series circuit relation. One side of one coil is connected by a conductor 12 in circuit with one side of a thermoelectric generator 13, and the other side of the other coil is connected by conductors 14 to the other side of the thermoelectric generator 13. The thermoelectric generator 13 is shown in the form of a thermocouple having elements of different thermoelectric characteristics joined at 15 to form the "hot" junction. The thermoelectric generator may be in the form of a thermopile, or of any other suitable form, and is disposed with the "hot" junction 15 in the pilot flame, or in position to be heated by the pilot flame when it is ignited.

Where the apparatus is used, for example, for controlling a heater, a thermostat 16 or any other control may be connected in series in the thermoelectric circuit to control such circuit, for example, by connecting it between the conductors 14. The thermostat 16 may be opened and closed in accordance with the temperature of the room or other space where the heater is a room or space heater, or the thermostat may be arranged to be opened and closed in accordance with the temperature of the water in the tank associated with the burner 1 where the heater is a water heater, or otherwise as desired. Moreover, a limit control or any other suitable or preferred control or combination of controls may be connected in series in the thermoelectric circuit.

The electromagnet is housed within a downwardly opening cup-shaped shell 17 which may, for example, be flanged outwardly at its lower end and secured to the adjacent part of the valve body 7 by a ring nut 18 screwed on the valve body. Where the shell 17 is formed of metallic material, insulating means may be provided where the conductors 12 and 14 enter the shell as well understood in the art.

The valve member 4 is moved upwardly and downwardly as viewed in Figure 1 to open and closed positions by a bellows 19. The closed end of the bellows 19 is secured at 20 to the adjacent end of the valve stem 21, and the inwardly opening lower end of the bellows is secured at 22 to the inwardly extending and inwardly opening neck 23 formed integral with a partition 24 and disposed at the axis thereof. The partition 24 seats on an annular seat 25 on the valve body and closes the adjacent end of the inlet chamber 26 within the valve body.

The outer marginal portion of the partition 24 is flanged outwardly. A flexible diaphragm 27 is fastened marginally to the outer end of the outwardly flanged portion of the partition 24 and, with the partition, forms a closed and sealed liquid or fluid chamber 28. This chamber 28 and the space between the neck 23 and the bellows 19 is filled, for example, with water, or water and alcohol, or any other suitable liquid or fluid. The partition 24 and diaphragm 27 are secured to the valve body by the ring nut 18.

In order to reduce the amount of volumetric

vibrations in the liquid or fluid body within the chamber 28 with changes in ambient temperatures, a large portion of the chamber 28 may be filled by a non-expansible plug or filler member 29. The plug 29 may be formed, for example, of an alloy known as Invar, which is an iron, nickel alloy having a composition about 63.8 Fe, 35 Ni, and 0.2 C. This alloy is insensitive to temperature changes.

10 The device is provided with an armature 30 which is biased downwardly, as viewed in Figure 1, by a coiled spring 31 interposed, for example, between the armature 30 and an annular shoulder 32 on the shell 17. The bias of the armature 15 by the spring 31 is in opposition to the magnetic bias of the electromagnet when it is powered or energized by the thermoelectric generator 13.

15 One of the essential features of the present invention is that the armature 30 moves only through a very minute air gap which is shown more or less illustratively at 33 with the valve member 4 in closed position. This air gap 33 may be of the order of a few ten-thousandths of an inch and preferably attaining one one-thousandth of an inch as maximum spacing. Accordingly, some suitable adjustment may be provided to position the electromagnet relative to the armature 30 and the diaphragm 27 so that the valve 4 may have a travel into engagement with 25 the valve seat 5 and away from the valve seat sufficient to pass gas freely through the valve body 7.

20 As illustrative of one suitable adjustment means for the foregoing purpose, the magnet frame 10 is shown provided with a threaded stem 34 which projects through the end of the shell 17 and has a nut 35 screwed thereon. By turning the nut 35, the position of the pole ends of the magnet frame 10 may be adjusted toward and away from the armature 30. A lock nut (not shown) or other suitable means may be provided for locking the magnet frame in the desired position.

25 The pilot burner 37, which is located in juxtaposition to the main burner 1 for igniting the main burner, is supplied with gaseous fuel by a pilot supply pipe 38. The pilot supply pipe 38 may be connected, for example, to the pipe 2 anterior of the valve 4, or through the valve body 7, or to any other source of fuel supply. The thermoelectric generator 13 is disposed with the "hot" junction or junctions thereof in the pilot flame or in position to be heated by the pilot flame when the pilot burner is ignited.

30 In order to permit the liquid or other fluid to flow freely in the chamber 28 and around the plug 29 from the large cross-sectional area of the chamber to the neck 23 of reduced cross-sectional area, and from the reduced neck to the 35 large cross-sectional area portion of the chamber, the plug 29 may be provided, for example, with slots 39 in opposite surfaces thereof. These slots 39 preferably extend entirely across the opposite faces of the plug 29 for the purpose set forth.

35 In the operation of the device, with the pilot burner 37 extinguished or the thermostat 16 or other control open, the thermoelectric circuit, which includes the coils 11, is deenergized. At this time the armature 30 is biased to retracted position separated from the pole faces of the magnet frame 10 by the very minute amount of the air gap 33. As previously set forth, this gap 33 may attain, for example, a maximum of substantially only $\frac{1}{1000}$ of an inch, and the valve 4

will be in engagement with its valve seat 5. As the armature 30 moves to retracted position it moves, by its cooperation with the diaphragm 27, the diaphragm downwardly as viewed in Figure 1 a substantially equal amount. This reduces the volume of the chamber 28 by approximately the cross-sectional area of the chamber times the minute movement of the armature.

Due to the relatively large cross-sectional area of the chamber 28, the amount of liquid displaced from the chamber 28 into the neck 23 and acting upon the bellows 19 to move the valve 4 downwardly to closed position will be sufficient to provide, by the minute movement of the armature, an increased movement of the valve member into engagement with its seat and away from its seat sufficient to pass gas freely through the valve body 7 for maintaining the desired flame at the main burner 1. A computation has been worked out with a 3-inch diameter diaphragm 27 and 1½-inch diameter bellows 19, and it has been found by comparison of area that over 3/100 of an inch opening may be obtained by the valve 4.

When the pilot burner 37 is ignited, the coils 11 are energized by the heat of the flame of the pilot burner on the "hot" junction or junctions of the thermoelectric generator 13. The magnetic flux created by the energization of the windings 11 moves the armature 30 to attracted position relative to the pole faces of the magnet frame 10 against the action of the spring 31. This increases the volume of the chamber 28 by the cross sectional area of this chamber, times the movement of the armature 30. At this time the pressure of the gas within the inlet chamber 26 of the valve body 7, plus any atmospheric pressure, will force the bellows 19 upwardly, and thus move the valve 4 to open position in amount considerably greater than the minute amount of movement of the armature 30 as described in connection with the closing of the valve 4.

It will thus be apparent that the present invention provides, by the very minute movement of the armature, for obtaining increased movement of the valve or other controlling means in amount, for example, for opening and closing the valve 4 sufficiently for its intended purpose. Moreover, the force of opening of the valve 4 may be substantial inasmuch as the attraction of the armature 30 may substantially cancel the pressure of the spring 31.

If the pilot burner 37 is extinguished, the device acts as a safety shutoff device for shutting off the supply of fuel to the main burner by the accompanying deenergization of the thermoelectric circuit and operation of the valve 4 to closed position. At the same time the device operates automatically again to open the valve 4 by the simple expedient of relighting the pilot burner. As a result, the thermostat 16, or other desired control or combination of controls, may be employed for opening and closing, or disabling and enabling the thermoelectric circuit. If the thermoelectric circuit is opened or disabled by such other control when, for example, the pilot burner 37 is lighted, the valve 4 will not be opened until the thermoelectric circuit is again closed or enabled by such other control. When the thermoelectric circuit is closed or enabled by such other control device or control devices however, the valve 4 will operate automatically to open position when the pilot burner 37 is ignited. If the pilot burner is not ignited, the valve 4 will not operate to open position until the pilot burner 37 is ignited and until the thermoelectric circuit is

closed or enabled, for example, by the thermostat 16 or other control device where such thermostat or other control device is present.

In the embodiment of the invention shown in Figure 2, the electromagnet may correspond, in general, with the electromagnet shown in Figure 1. It has a magnet frame 10' and coils 11' connected in circuit with the thermoelectric generator 13' by lead conductors 40.

The electromagnet is closed within a container or vessel 41, and has an armature 42 which, as before, moves only through a very minute air gap of the amount previously set forth or of other desired amount. The armature 42 is connected by a stem 43 to a piston or plunger 44 which operates, for example, in sliding engagement with the adjacent wall of the vessel 1 which serves as a cylinder for this plunger.

A tubular system has a bottom leg 45, a vertical leg 46 opening downwardly from the bottom of the vessel 41 to one end of the bottom leg, and a second vertical leg 47 extending upwardly to an upper leg 48, which upper leg 48 opens, for example, at its opposite end into the vessel 41 above the plunger 44. In this embodiment of the invention the tubular system may be formed of stainless steel or other suitable material for resisting attack by mercury. The space within the vessel 41 below the plunger 44 is filled with mercury, which also fills the legs 46 and 45 of the tubular system, and extends up into the leg 47, for example, to the position indicated at 49.

An electrode 50 may connect to the tubular leg 47 where this leg is formed of conducting material, or the electrode may extend into this leg and into electrical contact with the mercury 51 therein. In either case, the mercury 51 at the position 49 serves as one of the contacts of the switch or relay. A second electrode 52 may be sealed into the tubular system as, for example, by a glass seal or other suitable seal. The electrodes 49 and 52 are connected by conductors 53 and 54 in the circuit for the device which it is desired to control.

In operation of the device shown in Figure 2, minute movement of the armature 42 to retracted position produces increased movement of the mercury at the position 49 due to the relatively small cross-sectional area of the tubular system at position 49 as compared with the cross-sectional area of cooperation of the plunger 44 with the body of mercury within the vessel 41. The movement of the armature 42 to retracted position may be limited, for example, by cooperation of the plunger with the bottom of the vessel 41, or by other suitable stop means cooperating with the armature or with the plunger. The armature is moved to attracted position by energization of the electromagnet, as in the previous embodiment of the invention, and a spring 55 may be provided for moving the armature to retracted position with accompanying movement of the plunger when the electromagnet is deenergized.

As the mercury in the leg 47 is forced outwardly upon movement of the armature to retracted position, it contacts the electrode 52 and completes the electric circuit through the conductors 53 and 54. The device may, of course, within the scope of the present invention, be arranged to make contact and complete the circuit when the armature moves to attracted position, and to open the circuit when the armature moves to retracted position.

The embodiment of the invention shown in

Figure 3 is similar, in general, to the embodiment of the invention shown in Figure 2, except that the actuating structure is similar to the actuating structure shown in Figure 1. The bellows 19' opens into a vertical tubular leg 55, which in turn opens into the horizontal leg 56 of the tubular system. The horizontal leg 56 opens into a vertical tubular leg 57. The bellows 19' and the tubular system up to the position indicated at 58 in the vertical leg 57 is filled with mercury. The tubular system and bellows 19' may be formed of stainless steel to resist attack by the mercury.

An electrode 59 may connect to the tubular leg 57 where this leg is formed of conducting material, or the electrode may extend into this leg and into electrical contact with the mercury 60 therein. In either case, the mercury 60 at the position 58 serves as one of the contacts of the switch or relay. A second electrode 61 may be sealed into the tubular system as, for example, by a glass seal 62 or other suitable seal. The electrodes 53 and 61 are connected by conductors 63 and 64 to the circuit which it is desired to control.

In the device shown in Figure 3, a tubular leg or passage 65 extends from the vertical leg 57 to a casing or chamber 66 provided with a diaphragm 67. This diaphragm 67 cooperates in the tubular system in such manner that changes in atmospheric pressure affecting the first diaphragm (i. e., the diaphragm 27' of the actuator) are opposed by pressure acting on the second diaphragm 67. The tubular leg 65, as well as the chamber 66, and the interior of the vertical leg 57 above the mercury 60 therein are preferably filled with a suitable gas. In this respect, it is preferable to employ some inert non-oxidizing gas within the system, such, for example, as argon or the like.

The passage 65 may contain a porous plug 68 of such consistency or character that it will pass the gas within the system freely, but will stop or block off the flow of mercury. A fritted or sintered glass plug is contemplated for this purpose, but this is illustrative and not limiting.

It is believed that the operation of the device shown in Figure 3 will be clear from the descriptions of the operations of the devices shown in Figures 1 and 2.

The embodiments of the invention shown in the drawings are for illustrative purposes only, and it is to be expressly understood that said drawings and the accompanying specification are not to be construed as a definition of the limits or scope of the invention, reference being had to the appended claims for that purpose.

I claim:

1. In a device of the class described, in combination, an electromagnet, an armature biased to retracted position and movable to attracted position by energization of said electromagnet, a fluid containing cylinder having a first relatively small diameter portion and a second relatively large diameter portion between which fluid is adapted to be displaced by the movement of said armature to attracted and retracted positions, and control means operable to one of at least two different positions by the displacement of fluid from the first relatively small diameter portion of the cylinder to the second relatively large diameter portion of the cylinder and operable to the other of such two positions by displacement of fluid from the second relatively large diameter portion of the cylinder to the first relatively small

diameter portion of the cylinder, the two different positions of the control means being separated by an amount greater than the separation of said armature from said electromagnet when said armature is in retracted position.

2. A device according to claim 1 wherein the electromagnet has a winding connected in circuit with a relatively weak source of energy incapable of moving the armature a distance as great as the distance between the two positions of the control means.

3. A device according to claim 1 wherein the electromagnet has a winding connected in circuit with a thermoelectric generator for energization thereby.

4. A device according to claim 1 wherein the electromagnet has a winding connected in circuit with a thermoelectric generator for energization thereby, and condition responsive means in the circuit which includes the winding of the electromagnet and the thermoelectric generator.

5. A control device according to claim 1 wherein the control means comprises a safety shut-off valve connected to a flexible bellows responsive to the fluid displaced from the relatively large diameter portion of the cylinder to the relatively small diameter portion of the cylinder, and wherein at least one large diameter wall of the large diameter portion of the cylinder is formed by a flexible diaphragm actuated by the relatively minute movement of the armature to retracted position.

6. A control device according to claim 1 wherein the control means comprises a safety shut-off valve connected to a flexible bellows responsive to the fluid displaced from the relatively large diameter portion of the cylinder to the relatively small diameter portion of the cylinder, and wherein at least one large diameter wall of the large diameter portion of the cylinder is formed by a flexible diaphragm actuated by the relatively minute movement of the armature to retracted position, the relatively large diameter portion of the cylinder containing a non-expansible filler member for reducing the amount of volumetric variations in the fluid in said portion of the cylinder.

7. A control device according to claim 1 wherein the control means comprises a safety shut-off valve connected to a flexible bellows responsive to the fluid displaced from the relatively large diameter portion of the cylinder to the relatively small diameter portion of the cylinder, and wherein at least one large diameter wall of the large diameter portion of the cylinder is formed by a flexible diaphragm actuated by relatively minute movement of the armature to retracted position, the relatively large diameter portion of the cylinder containing a non-expansible filler member for reducing the amount of volumetric variations in the fluid in said portion of the cylinder, said filler member having slots extending across its opposite surfaces to permit free flow of the fluid around the filler member.

8. A control device according to claim 1 wherein the control means comprises spaced contacts, and a body of mercury disposed in the cylinder portion of relatively small diameter and actuated in a direction to control connection between said contacts by displacement of fluid between the relatively large diameter and relatively small diameter portions of the cylinder.

9. A control device according to claim 1 wherein the control means comprises spaced contacts, and a body of mercury disposed in the cylinder

portion of relatively small diameter and actuated in a direction to control connection between said contacts by displacement of fluid between the relatively large diameter and relatively small diameter portions of the cylinder, the relatively small diameter portion of the cylinder having an upper leg placing the small diameter portion of the cylinder above the body of mercury therein in communication with the large diameter portion of the cylinder above the means for displacing fluid from the large diameter portion of the cylinder to the small diameter portion of the cylinder.

10. A control device according to claim 1 wherein the control means comprises spaced contacts, a body of mercury disposed in the cylinder portion of relatively small diameter and actuated in a direction to control connection between said contacts by displacement of fluid between the relatively large diameter and the relatively small diameter portions of the cylinder, and a connected leg placing a diaphragm chamber having a diaphragm responsive to atmospheric pressure in communication with the small diameter portion of the cylinder between the spaced contacts.

11. A control device according to claim 1 wherein the control means comprises spaced contacts, a body of mercury disposed in the cylinder portion of relatively small diameter and actuated in a direction to control connection between said contacts by displacement of fluid between the relatively large diameter and the relatively small diameter portions of the cylinder, a connected leg placing a diaphragm chamber having a diaphragm responsive to atmospheric pressure in communication with the small diameter portion of the cylinder between the spaced contacts, and a plug in said connected leg of a character to pass gas freely but which will block the flow of mercury.

12. A control device comprising, in combination, a valve body having an inlet, and outlet, and a port provided with a valve seat, said valve

body having an outwardly opening tubular part in alignment with the valve seat, a partition seated on the outer end of said tubular part, said partition having an outwardly extending marginal flange of relatively large diameter and an inwardly extending tubular neck of relatively small diameter, a valve member movable into and out of cooperation with the valve seat, a flexible bellows of relatively small diameter disposed within said relatively small diameter tubular neck and connected to said valve member, a flexible diaphragm secured marginally over the marginal flange of said partition and with said partition defining a relatively large diameter chamber containing a fluid which is displaced from said large diameter chamber into said tubular neck and from said tubular neck into said large diameter chamber, an electromagnet comprising a magnet frame and a winding therefor, and a relatively large diameter armature for said electromagnet, said armature, when in retracted position, being spaced from the magnet frame by a minute air gap and acting against said diaphragm to displace fluid from said relatively large diameter chamber into said relatively small diameter neck whereby to impart increased movement to said bellows to close said valve.

SEBASTIAN KARRER.
